UNITED STATES PATENT OFFICE.

VICTOR GUINZBURG AND SAMUEL GLASS, OF NEW YORK, N. Y.

DESIGN FOR SUSPENDERS.

SPECIFICATION forming part of Design No. 12,955, dated June 6, 1882.

Application filed March 23, 1882. Term of patent 3½ years.

To all whom it may concern:

Be it known that we, VICTOR GUINZBURG and SAMUEL GLASS, citizens of the United States, residing in the city, county, and State of New York, have invented and produced a new and original design or pattern to be embroidered or otherwise worked upon an article of manufacture called "Suspenders," of which design the following is a specification, reference being had to the accompanying drawing, forming part thereof.

Our purpose in making this design has been to produce for sale suspenders with the initial letter of the purchasers' names embroidered or otherwise worked, together with a tasteful background or field, upon the conspicuous parts of the suspender-straps, by which design the suspenders are rendered more attractive and their salability greatly increased.

The characteristic features of this design are an initial letter, which may be any letter of the alphabet of the general character shown

in the accompanying drawing, and an ornamental field or background, encircling the letter, composed of the leaves and flowers, substantially as shown.

In the drawing only one end of one of the suspender-straps A with the embroidered letter upon it is shown; but we intend to place another letter upon the corresponding part of the other strap; nor is the number or place of the letters upon the straps essential to our design.

What we claim is—

A design to be embroidered, woven into, or otherwise wrought upon suspenders, consisting of a letter of the alphabet and a figured background, substantially as herein shown.

VICTOR GUINZBURG.
SAMUEL GLASS.
